UNITED STATES PATENT OFFICE.

FREDERICK BRADY, OF MIDDLETOWN, DELAWARE.

DRAWER-RACK.

1,191,657.

Specification of Letters Patent. Patented July 18, 1916.

Application filed February 7, 1914. Serial No. 817,243.

To all whom it may concern:

Be it known that I, FREDERICK BRADY, a citizen of the United States, and a resident of Middletown, in the county of New Castle 5 and State of Delaware, have invented an Improvement in Drawer-Racks, of which the following is a specification.

My present invention relates to drawer racks, and particularly to inclined partitions for use in desk drawers to form a plurality of paper compartments, the object of my invention being to provide partition members of such a structure as that each forms a paper holder and may receive selected sizes of sheets and the like, and at the same time maintain the outer edges of such sheets in substantially the same plane with the sheets of different sizes held by the other partition members.

20 A further object of my invention is to provide partition members so connected as that they may be held in a series within a drawer and remain at all times freely removable and, when so removed, may be 25 quickly and readily folded in compact form for transportation.

These and other objects and their resulting advantages will be apparent from the following description in which reference is 30 made to the accompanying drawing, forming a part of this specification, and in which—

Figure 1 is a vertical longitudinal section through a drawer in which my improved rack is disposed. Fig. 2 is a side view of the rack reversed and folded. Fig. 3 is a detail perspective view of one of the inner partition members. Fig. 4 is a similar view of an outer partition member. Fig. 40 5 is a vertical longitudinal section through the lower portion of one of the partition members and its base strip, and Fig. 6 is a detail perspective view of one end portion of one of the base strips.

45 Referring now to these figures, my improved rack consists of a plurality of partition plates A, A' and A², which are disposed in parallel relation and connected at their upper and lower ends by strips B 50 and B' in such manner as that the several partition members may be moved to vertical positions in which they are spaced a maximum distance from one another, or to horizontal positions in which they are in close contact and form a compact folded struc-

ture, which will utilize a minimum space in packing for transportation and in which the several parts being in contact with one another will mutually support one another and prevent distortion or breakage. This last- 60 mentioned position is clearly shown in Fig. 2, and for purposes of use the several partition members are opened and the structure after reversal may be disposed within a drawer, such as indicated generally at C 65 in Fig. 1 to assume inclined positions, the lower end of the rearmost member A engaging the rear end of the drawer, and the upper end of the foremost partition member A² engaging the forward end of the drawer 70 in order to support the rack therein.

To the end that the above connections may be conveniently made, I preferably construct each of the partition members of a section of sheet metal, the longitudinal side 75 edges of which are bent outwardly, forming flanges a therealong, which constitute the sides of the respective paper holding compartment. I also provide each of the partition members with series of key hole 80 slots a' adjacent opposite sides, with selected pairs of which a base strip D may be associated, each base strip having an upwardly inclined flange d and a pair of depending studs d', in the form of rivets having lower shoulders in order that they may be conveniently fitted into the said slots a' 85 in the manner best shown in Fig. 5. Each of these base strips necessarily causes the upper edges of the plurality of sheets in 90 the particular compartment to be disposed in inclined relation, holding the upper sheet in most convenient position for removal.

The connecting strips B and B' are pivotally united by small studs b to the side 95 flanges a of the several partition members adjacent the upper and lower ends thereof, and it is to be noted by comparison of the full and dotted lines in Fig. 1 and of Figs. 3 and 4, that the partition members, or one 100 or more of them, may be curved from the upper to the lower edges thereof in order to adapt the same to the reception of sheets of greater length than it would be possible for them to contain or hold if straight and 105 flat.

By adjustment of the base strip D through the means before described, either whole or various sized sheets may be disposed upon the several partition members with the up- 110

per edges of the entire series of sheets in substantially the same plane adjacent to the upper ends of the partition members.

The rack proposed by my invention may 5 be readily transferred from one drawer of a desk to another as the necessity for its transfer arises, will be simple and inexpensive to manufacture, and will be strong and durable in its use.

10 I claim:—

A drawer rack comprising a plurality of partition plates each of which consists of a body provided with longitudinal side flanges, strips pivotally connecting the side flanges of the plates adjacent the upper and lower ends whereby to permit the plates to

be folded or nested and to enable their disposition in variously inclined positions within a drawer, each of said plates being provided with longitudinal side series of key 20 hole slots and a base strip for each plate having depending and shouldered studs for engagement in selected key hole slots and having an upwardly projecting flange extending transversely across the partition 25 plate and inclined toward the upper end of the latter, all for the purpose described.

FREDERICK BRADY.
